UNITED STATES PATENT OFFICE.

FREDERICK A. PRESTON, OF HIGHLAND PARK, ILLINOIS, ASSIGNOR TO THE P. & M. CO., OF CHICAGO, ILLINOIS, A CORPORATION OF ILLINOIS.

ANTICREEPER.

1,228,597.

Specification of Letters Patent.

Patented June 5, 1917.

Application filed June 16, 1916. Serial No. 103,967.

To all whom it may concern:

Be it known that I, FREDERICK A. PRESTON, citizen of the United States, residing at Highland Park, in the county of Lake 5 and State of Illinois, have invented a certain new and useful Improvement in Anticreepers, of which the following is a full, clear, concise, and exact description.

My invention relates to improvements in 10 anticreepers or rail anchors.

An anchor has been developed heretofore consisting of a transverse member which grips one side of the rail base and has a dog or lock arranged to hold the other side to 15 the rail base. The dog has to be forced into position by hammer blows by driving it over the sharp upper edge of the base, which results in stretching it somewhat, whereby the frictional grip on the rail base 20 is not as great as it should be. Furthermore, there is little or no latitude whereby rail bases of different sizes may be fitted with the same standard anticreepers.

The object of the present invention is to 25 provide a structure in which these difficulties are obviated, whereby the rail anchor may maintain a firm frictional grip on the rail base throughout long continuous service and whereby the rail anchor will adapt 30 itself to slight variations in the dimensions of the rail base. This object is attained by a construction wherein a spring washer or other resilient member is so disposed with respect to the rail base and the two main 35 parts of the anti-creeper as to permit a yielding action when the dog is driven on to the rail base, thereby avoiding the distortion mentioned, insuring a firm grip of the anchor on the rail base under all conditions 40 of service and allowing some latitude for differences in the sizes of the rails. Other objects and advantages of the invention 45 will be apparent from the description hereinafter given of several embodiments thereof.

In the drawings—

Figure 1 is a top plan view of one form of anchor which embodies the invention;

Fig. 2 is a rear elevation thereof, partly 50 in section;

Fig. 3 is a section on the line 3—3 of Fig. 2;

Fig. 4 is a rear elevation, partly in section, of another form of rail anchor;

Fig. 5 is a section thereof on the line 5—5 of Fig. 4;

Fig. 6 is a rear elevation of a third form of rail anchor, and

Fig. 7 is a similar elevation of an additional form of anchor.

The anti-creeper illustrated in Figs. 1, 2 and 3 consists of a transverse member 1 beneath the rail base coöperating with a lock or dog 2 at one side of the rail base and having a resilient member in the form 65 of a spring washer 3 between the base of the rail 4 and said transverse member to maintain a firm frictional engagement of the parts on the rail base. The member 1 may be made of any suitable material. It 70 is illustrated in the form of a malleable iron casting so shaped as to permit of economical manufacture. The dog is made preferably from a steel plate. However I do not limit myself to these materials. The 75 casting is provided with an integral rail-gripping jaw 5 at one end and a downwardly extending rib 6 at the other end. An intermediate tie abutting flange 7 is also formed integrally therewith. In the upper 80 surface a recess 8 is provided, which in the present instance is of circular outline, to conform with the shape of the spring washer 3. Reinforcing ribs or walls 9 are arranged 85 adjacent to the rib 6, a notch 10 being provided between said walls to receive the dog 2 and permit the latter to bear against the lower surface of the rib 6.

In applying the anti-creeper to the rail, the spring washer 3 is placed within the recess 8 of the casting, after which the latter is hooked over one side of the rail base about as indicated in dotted lines in Fig. 2. The dog 2 is then hooked over the rib 6 and over the opposite side of the rail base, as shown 95 also in dotted lines in said figure. The casting is then forced to the left so as to fit the jaw 5 firmly over the rail base, and the dog 2 is forced upwardly over the opposite side of the rail base until the parts finally assume 100 the position shown in full lines in said figure. During this action the spring washer 3 is compressed and thereafter it exerts a downward thrust against the casting whereby the dog maintains a firm frictional engagement on the rail base. It will be seen that, in the absence of the spring washer, as 105 the dog is swung to the final position it

would be elongated or stretched somewhat in forcing it over the edge of the rail, unless the casting yielded somewhat, or if said dog or casting did not yield materially the corner of the rail base might be worn off somewhat, giving a slightly rounded edge, as a result of which it would not be as difficult to remove the clip as would otherwise be the case. With the arrangement herein illustrated, however, the line representing the downwardly inclined thrust of the clip against the top of the rail base passes through the point of contact of the dog with the rib 6 and through the rail base at a point somewhat in from the edge of the rail, whereby there is no tendency for the dog to slip off the rail. Furthermore slight variations in the dimensions of the rail base do not affect the security of the engagement, owing to the action of the spring washer. After the anchor has once been positioned on the rail base it is positively locked against movement toward either side. The creeping of the rail causes the flange 7 to exert a thrust against the tie 11, resulting in a slight tilting of the dog 2 which tends to further increase the grip of the anchor on the rail base. However, the security of the engagement is not dependent on such coöperation with the tie, and furthermore if the rail moves rearwardly there is no relaxation of the grip. In fact, if the flange 7 becomes embedded in frozen ballast a rearward movement of the rail would be resisted by said anti-creeper.

In the form of anti-creeper shown in Figs. 4 and 5, a spring washer 12 is arranged between the two main parts of the anti-creeper 13 and 14, although not in actual contact with both of them. The dog 14, instead of bearing directly against the rib 15 on the main member 13, bears against an intermediate piece 16. Said piece has a curved end 17 which fits over the rib 15 and is in turn embraced by the lower end of the dog 14. It receives the downward thrust of the spring washer 12, which thrust is transmitted to the dog 14, thereby maintaining the firm frictional engagement of the parts. An important advantage of this relative arrangement is that there is also an upward thrust or reaction exerted by the spring washer 12 against the main part 13 of the anchor, which results in pressing said main part firmly upwardly against the rail base, thereby increasing the frictional hold of the rail anchor on the rail base. In other words, the effect is such as to tend to press the two main members of the anti-creeper apart at the point where they coöperate beneath the rail. It also tends to press them toward each other in the sense that the transverse member presses upwardly against the rail base and the upper part of the dog is forced downward against the top of the rail base,

whereby the latter is clamped between the two.

The action of this anchor in resisting creeping in both directions is substantially the same as that previously described.

In Fig. 6 I have illustrated another type of rail anchor, which permits a greater degree of adjustment with respect to rails of different dimensions. The main member 18 of the anti-creeper is provided with a series of ribs or teeth 19 which engage corresponding teeth 20 on the dog 21. A spring washer 22 is also provided, the action of the latter being similar to that described in connection with Figs. 1, 2, 3. The teeth permit locking engagement between the member 18 and the dog 21 at various points of adjustment of said parts toward or away from each other, whereby when said parts are simply driven together they will coöperate to grip rail bases of various sizes.

In Fig. 7 I have illustrated a further form of anti-creeper, which combines the functions of those shown in Figs. 4 and 6. The spring washer 23 is arranged between the main member 24 and the auxiliary member 25, which latter is provided with teeth coöperating with teeth on the dog 26. The two main parts of the anti-creeper are therefore pressed apart and held in firm frictional engagement with the rail base in the manner previously described. Furthermore, the anchor is adapted to fit rails of radically different sizes and maintain an effective hold thereon.

It will be understood that the various embodiments of the invention herein shown are intended to illustrate the several features of the invention but are not intended to limit the same to said forms, as various other embodiments of the invention may be devised which fall within the scope of the appended claims.

Having thus described my invention, what I claim as new and desire to secure by Letters Patent of the United States is:

1. An anti-creeper comprising a member beneath the rail base having a jaw fitted over one side of the latter, a dog engaging said member beneath the rail base and fitting over the top of the latter to draw said member upwardly against the rail base and a third member coöperating with said parts to increase the frictional engagement between them and the rail base.

2. An anti-creeper comprising a transverse member having a jaw fitting one side of the rail base, a dog engaging the other end of said member beneath the rail base and fitting over the top of the latter to hold said member to the rail base and a spring washer carried by one of said members.

3. A rail anchor comprising a transverse member having a jaw gripping one side of the rail base, a steel plate engaging

the other end of said member beneath the rail base and fitting over the top of said base and a spring washer arranged to exert a downward thrust on said steel plate.

- 5 4. An anti-creeper comprising a casting having a tie abutting flange, a downwardly projecting rib at one end, a rail gripping jaw at the other end and a spring washer seated in a recess in said casting.
- 10 5. An anti-creeper comprising a transverse member beneath the rail base, a dog fitting over the top of said rail base and beneath said member and a spring washer arranged intermediate said members, where-
15 by it exerts an upward thrust on one and a downward thrust on the other.

6. An anti-creeper comprising a casting having an integral jaw thereon and a tie abutting flange, a dog, a member between
20 said dog and said first member and a resil-
ient member arranged to press said first and second members apart.

7. An anti-creeper comprising a trans-
25 verse member having a jaw at one end, a
downward extension at the other end, a mov-
able piece associated with said member and
adjacent to said extension, a resilient mem-
ber arranged to press said piece away from
30 said extension and a dog to resist such

8. An anti-creeper comprising a trans-
verse member having a jaw at one end, a
downward extension at the other end, a mov-

able piece associated with said member and
adjacent to said extension, a resilient mem-
ber arranged to press said piece away from
35 said extension, a dog to resist such action
and teeth on said dog and said piece to per-
mit adjustment of the anchor to rails of dif-
ferent sizes.

40 9. An anti-creeper comprising a member
arranged transversely beneath the rail base,
a jaw at one end thereof, a dog to hold the
other end thereof to the rail base, teeth on
45 said dog to permit coöperation between said
parts at a plurality of positions of relative
adjustment and resilient means for main-
taining such coöperation.

10. An anti-creeper comprising a trans-
verse member beneath the rail base, means
50 for holding said member to the rail base on
one side, a notched plate arranged to em-
brace the other side of the rail base and said
member to hold the latter to the rail, said
plate when it is being positioned acting mo-
mentarily to clamp said member more
55 closely against the rail base than when in
final position, and additional means ar-
ranged to yield during said positioning
movement and thereafter to maintain the
parts in yielding frictional engagement with
60 the rail base.

In witness whereof I, hereunto subscribe
my name this 6th day of June, A. D., 1916.

FREDERICK A. PRESTON.
